(57) **CLAIM**

The ornamental design for a flosser body, as shown and described.

DESCRIPTION

FIG. 1 is a perspective view of a flosser body showing the new design.

FIG. 2 is a front view of the flosser body of FIG. 1.

FIG. 3 is a back view of the flosser body of FIG. 1.

FIG. 4 is a left side view of flosser body of FIG. 1.

FIG. 5 is a right side view of flosser body of FIG. 1.

FIG. 6 is a top view of flosser body of FIG. 1; and,

FIG. 7 is a bottom view of flosser body of FIG. 1.

The broken lines shown in the drawings depict portions of the flosser body that form no part of the claimed design.

1 Claim, 4 Drawing Sheets(56)
